Patented Sept. 5, 1911.

Application filed June 12, 1911. Serial No. 632,797. Term of patent 7 years.

To all whom it may concern:

Be it known that I, RICHARD H. WELLES, a citizen of the United States, residing at Kenosha, in the county of Kenosha and State of Wisconsin, have invented a new, original, and ornamental Design for Headlights, of which the following is a specification, reference being had to the accompanying drawings, forming a part thereof.

In the drawings, Figure 1 is a side elevation of my new design, and Fig. 2 a rear end elevation thereof.

The lamp has as its distinguishing feature the exterior polygonal contour of its parts. The barrel or main body portion 1 is octagonal as to its exterior and is provided with an oil font 2, the main body portion of which is similarly polygonal, and a tired top ventilator 3 having polygonal rims 4. The door 5 and the handle 6 are of substantially the same exterior configuration.

I claim:

The ornamental design for a headlight as shown and described.
